9797X

A. Wood,

Rocking Chair,

Patented June 28, 1836

6/28/1836

9797X

Andrew Woods

June 28, 1836

The author of this note is Andrew Woods and writing from the village of New Haven, Connecticut to his son Andrew Woods, Jr. He is writing on the occasion of the marriage of his son to a Miss Maria Weston, and is expressing his pleasure and pride in his son's choice of a wife. He writes that he has known Maria Weston for a long time and has always been pleased with her character and conduct. He describes her as a young woman of great beauty and grace, with a kind and gentle disposition, and loving affections, and is looking forward to her marriage with his son with great pleasure. He wishes his son to be happy and successful in his new life, and to always remember his mother and his family. He also expresses his hope that his son will be a good husband and father, and that he will be a credit to his wife and to the family. He concludes by expressing his best wishes for the happiness of his son and his new wife, and by bidding them a fond farewell.

6/28/1836

9797x

(6) 28) 1836

9797X

790 words Present since 1/21/

1880-1881